UNITED STATES PATENT OFFICE.

JOSEPH C. HOBRECHT, OF SACRAMENTO, CALIFORNIA.

DESIGN FOR A SEMI-INDIRECT-LIGHTING FIXTURE.

49,185.

Specification for Design.

Patented June 13, 1916.

Application filed May 1, 1916. Serial No. 94,837. Term of patent 7 years.

To all whom it may concern:

Be it known that I, JOSEPH C. HOBRECHT, a citizen of the United States, residing at Sacramento, in the county of Sacramento and State of California, have invented a new, original, and ornamental Design for Semi-Indirect Lighting-Fixtures, of which the following is a specification, reference being had to the accompanying drawings, forming part thereof.

Figure 1 is a side elevation of the lighting fixture. Fig. 2 is a bottom view of same.

I claim:

The ornamental design for a semi-indirect lighting fixture, as shown.

J. C. HOBRECHT.

Witnesses:

JOHN McCARTY,
F. A. AUKMER.
